United States Patent

Des. 236,766

Patented Sept. 16, 1975

236,766

CHILD'S SWING SEAT

Gregory B. Speer, St. Clairsville, Ohio, assignor to
Blazon-Flexible Flyer, Inc., Medina, Ohio

Filed Dec. 20, 1973, Ser. No. 426,959

Term of patent 14 years

Int. Cl. D6—01

U.S. Cl. D6—10

FIG. 1

FIG. 2

FIG. 3

FIG. 4

FIG. 5

FIG. 6

FIG. 1 is a top plan elevational view of a child's swing seat embodying my new design.

FIG. 2 is a side elevational view thereof.

FIG. 3 is a front elevational view thereof.

FIG. 4 is a rear elevational view thereof.

FIG. 5 is a sectional view thereof on line 5—5 of FIG. 1.

FIG. 6 is a bottom plan elevational view thereof.

I claim:

The ornamental design for a child's swing seat, as shown.
